No. 657,408.

Patented Sept. 4, 1900.

F. GIELOW, SR.
LUBRICATOR.

(Application filed Oct. 7, 1899.)

(No Model.)

UNITED STATES PATENT OFFICE.

FREDERICK GIELOW, SR., OF CHICAGO, ILLINOIS.

LUBRICATOR.

SPECIFICATION forming part of Letters Patent No. 657,408, dated September 4, 1900.

Application filed October 7, 1899. Serial No. 732,837. (No model.)

To all whom it may concern:

Be it known that I, FREDERICK GIELOW, Sr., a citizen of the United States, and a resident of Chicago, in the county of Cook and State of Illinois, have invented certain new and useful Improvements in Lubricators, of which the following is a specification, and which are illustrated in the accompanying drawings, forming a part thereof.

10. This invention relates to that class of lubricators usually employed for introducing a lubricant into a steam-cylinder or the like and to the top and bottom of which the steam-pressure is applied.

15. The object of this invention is to adapt lubricators of this class for the practical use of graphite as a lubricant; and it consists, essentially, of means for effecting the discharge of the graphite from the lubricator by means 20 of a carrier having a pocket adapted to receive the graphite and from which pocket the lubricant is forced by the pressure of the steam-pipe, means being provided for agitating the lubricant within the reservoir sufficiently to prevent it from becoming impacted.

The invention consists, further, in the various details of construction, as hereinafter fully described, and as illustrated in the accompanying drawings, in which—

30. Figure 1 is a side elevation, partly in central section, of the improved lubricator. Fig. 2 is a detail section on the line 2 2 of Fig. 1. Fig. 3 is a plan section on the line 3 3 of Fig. 2, and Fig. 4 is a detail elevation of the carrier used for transferring the lubricant.

35. In carrying out my invention I use a reservoir or cup, preferably in the form of a cylinder 10, within which is located a follower 11. Across and opening to the bottom of the cylinder 10 there is located a barrel 13, within which plays a plunger or carrier 14, the inner surface of the bottom of the cylinder being recessed or depressed below the upper line of the barrel, as shown at 50, and through

40. a portion of its area being depressed approximately to the bottom of the barrel, as shown at 51, for the purpose hereinafter more particularly pointed out. The carrier 14 is provided with a stem 15, projecting through a 45 stuffing-box 16 at one end of the barrel 13 and being connected by means of a pitman 17 and a crank-pin 17^a with a ratchet-wheel 18, driven

by means of a spring-pawl 19, carried by a lever 20, which may be caused to oscillate by any desired means. The carrier 14 is provided with a pocket opening at its upper and lower side and being preferably in the form of an annular groove 21, which as the carrier reciprocates communicates alternately with the chamber of the cylinder 10 and with a delivery-duct 22, leading downwardly from the barrel 13 through the nipple 22^a, and which is connected with a steam-pipe 23 by means of a coupling 24, in the form of a sight-glass tube, and which incloses the usual tube-section of glass 25. At the intersection of the nipple 22^a with the coupling 24 there is placed a nozzle 26, which causes the lubricant to enter and pass through the glass tubular section 25 in small masses, thereby affording a sight-feed. A steam-pipe 27 leads from above to the upper end of the cylinder 10, and a branch thereof (shown as a duct 28) leads to the barrel 13 and opens thereto in alignment with the duct 22, so that when the groove or pocket 21 is in register with the latter duct it is also in register with the duct 28, and hence the pressure in this duct causes the discharge of the lubricant from the groove. When the groove 21 is in communication with the chamber of the cylinder 10, it is filled with the lubricant by reason of the downward pressure of the follower 11 due to the steam-pressure and to its weight and that of the water of condensation above it, so that each time the plunger or carrier 14 advances it carries a pocketful of the lubricant to the duct 22, into which it is discharged in the manner hereinbefore described. The carrier 14 is provided with a longitudinal duct 29, whereby a balance of pressure is insured at its opposite ends, so that it is free to reciprocate. A guide-stem 30 leads upwardly from the follower 11 into a glass tube 31, provided for its accommodation.

The lubricator may be adapted for use in connection with two engines by providing its carrier 14 with a second annular pocket 34, which will alternately enter the chamber of the cylinder 10 and register with a duct 35, leading downwardly from the end of the barrel opposite that at which the duct 22 is located. The connections leading from this

duct being identical with those leading from the duct 22, they need not be described. Steam-pressure may be applied to the barrel 13, so as to discharge the lubricant from the 5 pocket 34 into the duct 35 in any desired manner. For this purpose I show a pipe 36, leading to a duct 37, cored in the wall of the cylinder 10, this steam-passage being provided with a suitable valve 38, as is also the passage 28, as shown at 42.

The recess at the bottom of the cylinder 10 constitutes its eduction-port, and extending below the top of the carrier 14 the pockets 21 15 34 are open widely to the chamber of the cylinder 10, and this bottom being through a portion of its area depressed nearly to the bottom of the barrel 13, as shown at 51, the lubricant is free to enter the pocket from above and both sides of the carrier.

20 A scraper or agitator 52 is fixed upon the carrier 14, so that it may travel from end to end of the open portion of the barrel 13—that is to say, from the solid line to the dotted line position in Fig. 3—thereby loosening or agitating the contents of the cylinder as the carrier is reciprocated and preventing the lubricant from becoming impacted and from arching around the upper face of the carrier, so as to allow the pocket to slide through the 25 arch without being filled. While I have shown this scraper as being in the form of an arm fixed transversely across the carrier, it may be of any other desired shape, or, if preferred, may be actuated by other means than those 30 disclosed.

A vent and draining cock 53 of ordinary form opens through the bottom of the cylinder 10 for the purpose of facilitating the withdrawal of the follower 11 and to provide for 40 draining off the water of condensation preliminary to recharging the cylinder with lubricant.

While I have shown pockets in the carrier 14 as annular, they may be given any desired 45 form, provided only that they are adapted to receive the lubricant from the cylinder or cup 10 and to register simultaneously with a pressure-duct and with one of the receiving and conveying ducts 22 35.

50 The lubricator may be supported in any desired manner. I show it as being provided with a threaded stem 46, which forms a convenient means for attaching it to a rigid support.

55 I am aware that it has been proposed to provide lubricators with oscillating or reciprocating carriers for transferring the lubricant in measured quantities from a reservoir or cup to a conveying-tube; but I believe myself to be the first to provide in a lubricator of this type means for applying fluid-pressure directly to the contents of the pocket of the conveyer for the purpose of ejecting the same therefrom into the conveying-tube. The advantage of this in the use of graphite as a lubricant is that the fluid applied under pressure breaks up or disintegrates the material,

thereby not only loosening it from the receptacle of the carrier into which it is necessarily solidly compressed, but facilitating its passage along the duct of the conveying-tube, the fluid which has loosened it from the conveyer serving also as a vehicle for carrying it along the tube.

While I have hereinbefore referred to the 75 lubricator as being in use in connection with steam-pressure, I do not desire to be limited to such application of the invention, as any fluid under pressure may be used effectively 80 for the purpose described.

The operation of the herein-described lubricator is as follows: The cylinder 10 having been properly supplied with graphite, the valves in the pipes 27 and 23 are opened, thereby providing for the application of pressure 85 to the upper face of the follower 11 and within the duct 28. The conveyer 14 is caused to reciprocate by means of the lever 20. The agitating-arm 51 stirs up the graphite sufficiently so that under the pressure applied 90 to the follower 11 it will fill the pocket in the carrier, and when the latter is brought into register with the duct 28 and nipple 22 the pressure within the former will dislodge the graphite from the pocket, causing it to fall 95 into the nipple and to be conveyed therefrom through the pipe 23 to its ultimate destination, the water of condensation within the duct 28 serving as a vehicle for conveying it 100 through the latter tube.

When the lubricator is intended for use in connection with two cylinders or other parts to be lubricated, the valve in the service-pipe 36 is opened, and the action upon that side of the lubricator is the same as upon the opposite side.

Should it be desired to deliver the lubricant through the nipple 35 only, the valve in the duct 28 is closed by means of the valve-stem 42, so that no pressure will be applied 110 to the pocket 21, and hence it will not be dis-charged of its contents.

I claim as my invention—

1. In a lubricator, in combination, a reservoir, a barrel crossing the bottom of the reservoir and open thereto, a delivery-duct leading laterally from the barrel, a pressure-duct entering the barrel on the same transverse plane thereof with the delivery-duct, a carrier having a pocket adapted to open alternately 115 to the chamber of the reservoir and to the pair of ducts, and means for causing the reciprocation of the carrier.

2. In a lubricator, in combination, a cylinder having a discharge-aperture, a follower 125 in the cylinder, a barrel across the bottom of the cylinder and to which the discharge-aperture thereof opens, a carrier adapted to reciprocate in the barrel and having a pocket, a steam-service pipe leading to the top of the 130 cylinder 10, and to the barrel, and a receiving-duct leading from the barrel in line with the steam-service pipe.

3. In a graphite-lubricator, in combination,

a reservoir, a barrel crossing the reservoir and open thereto, a reciprocating carrier within the barrel and having a pocket and an agitating-arm which projects into the reservoir, and 5 a conveying-duct for receiving the contents of the carrier-pocket.

4. In a graphite-lubricator, in combination, a reservoir, a barrel crossing the reservoir and open to its chamber, a carrier adapted to reciprocate within the barrel and having a pocket, an agitating-arm mounted upon the carrier and projecting into the reservoir, a conveying-tube and a pressure-duct open to the barrel, the pocket of the carrier being 15 adapted to register with the tube and duct simultaneously.

5. In a graphite-lubricator, in combination, a reservoir, a barrel crossing the bottom thereof, a reciprocating carrier in the barrel and 20 having a pocket in the form of a circumferential groove, the bottom of the reservoir being depressed below the axis of the carrier, and a conveying-tube for receiving the lubricant from the carrier-pocket.

6. In a graphite-lubricator, in combination, 25 a reservoir, a barrel crossing the bottom thereof, a reciprocating carrier in the barrel and having a circumferential groove, the bottom of the reservoir being depressed below the axis of the carrier, means for agitating the 30 lubricant within the reservoir, and a delivery-tube for receiving the lubricant from the carrier-pocket.

7. In a graphite-lubricator, in combination, 35 a reservoir, a barrel crossing the bottom thereof, a carrier adapted to reciprocate in the barrel and having a circumferential groove, the bottom of the reservoir being recessed to uncover the groove below the axis of the carrier, an agitating-arm fixed upon the carrier and 40 projecting into the reservoir, and a conveying-tube for receiving the lubricant from the carrier-groove.

FREDERICK GIELOW, SR.
